UNITED STATES PATENT OFFICE.

RUDOLF EICKEMEYER, OF YONKERS, NEW YORK.

DEVICE FOR TAKING ELECTRIC CURRENTS FROM OR TO MOVING SURFACES.

SPECIFICATION forming part of Letters Patent No. 351,907, dated November 2, 1886.

Application filed December 3, 1885. Serial No. 184,545. (No model.)

To all whom it may concern:

Be it known that I, RUDOLF EICKEMEYER, of Yonkers, in the county of Westchester and State of New York, have invented certain new and useful Improvements in Devices for Taking Electric Currents from or Conveying them to Revolving or Moving Surfaces; and I do hereby declare that the following specification, taken in connection with the drawings furnished, and forming a part of the same, is a clear, true, and complete description of the several features of my invention.

Devices for the purpose stated have heretofore been usually designated by the general term, "brushes," regardless of their specific construction. As a rule, such brushes have been masses of wire arranged like the bristles of an ordinary brush; but in some cases flat plates or springs have been employed, both singly and in groups, and in other cases rollers backed by springs have been employed for obtaining a rolling-contact, and in this connection it is also to be understood that roller-contacts have heretofore been composed of cup-shaped disks, presenting in mass a peripheral contact-surface for engaging with the periphery of a co-operating wheel or hub; or, in other words, such roller-contacts have been organized to engage with surfaces parallel with their axes, whereas I have specially provided for contact with co-operating surfaces at right angles to the axis of the brush.

The main object of my invention is to obtain a reliable and durable electrical contact with a minimum resistance, and in that connection I have for the first time, as I believe, devised for use with the revolving device, from or to which an electric current is to be taken or applied, a brush or its equivalent of any kind which is rotated positively, as distinguished from being rotated by reason of its mere frictional contact with another revolving surface with which it electrically engages. For obtaining the best results, said brush or its equivalent should be thus positively rotated at a speed much less than the revolving surface with which it engages, although, should this latter be revolved at specially low speed, the brush or its equivalent should be revolved at a slightly higher speed, and hence this matter of relative speed should be determined according to circumstances in each case. This par-

ticular feature of my invention is obviously not dependent upon any particular construction of the brush or its equivalent; but for obtaining an extraordinary degree of efficiency and durability I have devised a disk-shaped conductor, (which may be properly termed a "brush,") which is broadly new, in that it is disk-shaped and composed of a series of laminations or plates placed side by side and clamped together, so that each can engage, under yielding pressure, with any surface with which the disk may be used as an electric conductor, and the contact surfaces of these disks and the several plates are presented in a plane at right angles to the axis of the brush, or at least in a plane which is not parallel with said axis, as distinguished from ordinary roller-contacts which have contact-surfaces parallel with their axes, and also as distinguished from certain solid roller-contacts heretofore used by me, having either wedge-shaped or inclined grooved peripheries.

In their best form, the plates of which my novel brushes are composed are peculiarly cut, so that when placed side by side and spirally arranged, each of the plates in any one series will present a portion of its side, near its periphery, in a plane substantially common to all of the plates in said series, and hence as the disk is revolved, flatly pressing its side, near its periphery against any smooth surface, each disk will have its individual contact-point during its proportion of the rotation of said disk. In another form said plates are of successively greater diameter, and near its periphery each plate is annularly concavo-convex, so that the edge of each will occupy a plane common to all, and hence each will press edgewise against any surface with which the disk may be placed in lateral contact at that portion of its periphery occupied by the edges of said plate.

Electric brush conductors embodying my invention differ radically from all roller-contacts heretofore known. Said roller-contacts operate only with peripheral engagement, and hence the surface area of contact is so slight as to involve high resistance, and the least oxidation of said surfaces results in varied conductivity. My brushes operate without peripheral engagement, but with a broad plane surface, and with such an extensive area of contact

that resistance is reduced to a minimum, and any ordinary spots of oxidation fail to impair their efficiency. My brush-conductors also radically differ from the ordinary flat-wire 5 brushes and flat-plate brushes, in that these maintain fixed relations at their contact-points, while mine, being in disk form and rotatively mounted, can be frequently or continuously varied with relation to their contact-points, 10 not only without deranging their conductive capacities, but in fact improving them.

For securing a reliable electric contact as between the several plates in each disk or in each series of plates, and also for lubricating their 15 contact-points, I employ a mercury-bath in which a portion of each disk is always immersed.

I am aware of the varied use of mercury as an intermediate conductor, as between moving and stationary conductors, and it is to be distinctly understood that I make no claim thereto other than as a lubricating medium, and in combination with a positively-driven brush, and especially in combination with a 25 brush composed of a series of laminations or plates clamped together, so that each of said plates can separately afford a yielding contact-surface.

The prime value of my present improvements accrues in connection with their use in electric generators or electric motors, and although I have illustrated said improvements in connection with certain dynamo-electric machines heretofore devised by me, and also 35 in connection with other forms of well-known dynamo-electric machines, it is to be understood that my present application is to be in no manner limited to machines of any particular kind, or to such as are organized for 40 any special purpose.

After describing the several illustrations of my present improvements, which are presented in the accompanying drawings, the novel features to be embraced in this application will 45 be specified in the several clauses of claims hereunto annexed.

Figure 1 illustrates a portion of my improvements in a desirable form as applied to a unipolar dynamo-machine, this latter being shown 50 partly in plan and partly in horizontal longitudinal section. Fig. 2 illustrates a bar and its conducting-rings detached from an armature of the machine shown in Fig. 1. Fig. 3 illustrates in section said bar and one of its 55 conducting-rings in working relation with one of my novel brush-conductors, also shown in section. Fig. 4 illustrates the conducting disk or brush shown in Fig. 3 in five views—viz., a side view and edge view of one of the plates, 60 two inside or coincident face views of the two halves of said brush, and an outside view applicable to either half thereof. Fig. 5 is a view of one end of a machine similar to that shown in Fig. 1, but with a set of the conducting-disk brushes organized so as to be positively 65 rotated. Fig. 6 illustrates in section a portion

of Fig. 5 on line *x*. Fig. 7 is a side view of one of the peculiar laminations or plates detached from a conducting disk or brush of the form shown in Fig. 5. Fig. 8, in central vertical section, illustrates another form of dynamo-machine embodying my improvements, in connection with an armature having conducting-rings of another form. Fig. 9 is an end view of the machine, Fig. 8. Fig. 10 illustrates an armature-bar, its ring, and my novel conducting-brush, in side view, detached from the machine. Fig. 11 in side view illustrates one form of plate detached from the conducting-brush, said plate being like that shown in Fig. 7. Figs. 12 and 13 illustrate, respectively, in horizontal and vertical longitudinal section, the hub or one end of a dynamo-armature of a well-known form and my positively-driven conducting-brushes applied to the opposite 85 sides of said hub. Fig. 14 illustrates the same, partially in end view and partially in transverse vertical section. Fig. 15 illustrates the same in end view. Fig. 16 illustrates in section one of my conducting-disks in a practical 90 form.

Referring to Fig. 1, it need only be understood, for the purposes of this specification, that the machine thereby partially illustrated is of the unipolar variety, and contains two 95 revolving armatures, *A* and *A'*, each embodying a series of conducting-bars, *a*, on each of which there are two conducting-rings, *b*, and that the several conducting-bars in one armature are electrically coupled to corresponding 100 bars in the other, so as to form one or more linear series of bars, and also that the said coupling of these bars is accomplished by means of intermediate conductors.

The only features which directly relate to 105 my present improvements are the intermediate conductors, *B*, here used with conducting-rings *b* of a novel form. In somewhat similar machines I have heretofore employed conducting-rings having flat peripheries, and the novel 110 feature now disclosed in that connection is a peripheral flange, *b'*, on said rings, whereby a more extended contact-surface is afforded for each ring than when a flangeless ring is employed. The flange *b'* may be so organized 115 with an intermediate conductor that but one side of said flange will serve as a contact; but, as shown in Figs. 1, 2, and 3, said flange is angular or wedge-shaped, and both of its sides serve as contact-surfaces. The conductors *B*, 120 as here shown, are disk-shaped, and are axially mounted upon a shaft, *c*, and in similar machines I have heretofore employed disks thus mounted; but said prior disks were substantially solid and flat-faced at their peripheries, and engaged with peripheral rolling-contact with one or two of the flat-faced conducting-rings. The conductors or brushes *B*, as here shown, are novel in that they are composed of two separate series of laminations or plates, each substantially of disk form, 125 but so shaped and spirally arranged with re-

lation to each other that although said plates are massed side by side a portion of each affords a contact-surface for electrically engaging with one side of a conducting-ring flange.

5 In Fig. 4, at the left-hand portion thereof, one of these plates d is shown in side view and also in edge view. It has an axial opening at d' and a radial slit at d'' extending from said opening to its periphery; also a circular outline at d^3 extending throughout, say, half its circumference, and an eccentric outline at d^4 extending from said radial slit throughout, say, the remaining half of its circumference. These particular conducting-brushes embody two series or sets of said plates, and their coincident faces are illustrated by the two central portions of Fig. 4, while the back of either set or series is illustrated by the right-hand portion of Fig. 4.

20 From these figures and the description thus far given it will be readily understood that each of the several plates presents a portion of its side, near its periphery, as a contact-surface, available for engaging with a revolving 25 or other surface, with which it is to electrically engage. These plates d are composed of any good conducting material, and are preferably more or less resilient, so that they will operate with a yielding or spring contact. Two sets 30 or series of plates being used, as shown, enables the flange b' of a conducting ring to be snugly embraced, and as every one of the plates in both series serves as a conductor such brushes are not only thoroughly reliable 35 and effective in their operation, but the distribution of wear is so uniform that they are of great durability. It is to be understood that I do not limit myself to this particular cut or form of plate or lamination, it being 40 broadly new, as I believe, to combine in an electric-brush conductor a series of plates or laminations, however cut or formed, in which all the plates have their separate or individual contact with the moving surface with which 45 said plates are operated as electric conductors.

For illustrating a practicable variation in the cut and form of the laminations or plates, I will refer to Fig. 7, in which the plate d is circular in its outline, instead of eccentric, 50 but it has the radial slit d'' and axial opening d' , before described. This plate has, however, a portion of its interior cut away on eccentric lines, extending from said radial slit, so that when a series or set of these plates are placed 55 side by side and spirally arranged and clamped on their shaft c , each plate presents a portion of its side, near its periphery, as a contact-surface, which can either be pressed flatly against one side of a conducting-ring or the flange of 60 the latter may be embedded therein. The long curved tongues on these plates render this form of brush highly elastic or resilient at its contact-surfaces.

In Figs. 5 and 6 portions of a dynamo are 65 shown, in which a lower set of brushes B co-operate with an upperset, (shown partially in

Fig. 1,) for coupling the armature-bars in linear series. The lower brush-shaft, c' , is below and parallel with the upper brush-shaft, c , and with the axes of the armatures A and A' . 70

I will next describe how the several conductors or brushes B are positively driven or revolved, and this I deem a broadly novel feature, regardless of the character of the machine in which said brushes are or may be 75 used, and also regardless of any particular form or construction of the brush itself. As a source of power for revolving said brushes and their shaft, any adjacent revolving shaft may be relied upon; but in such machines I 80 prefer to use an armature-shaft, e , and, as here shown, said shaft at its outer end is provided with a thread or worm, e' , which meshes with a worm-gear, e^2 , on a horizontal shaft, e^3 , also provided with a thread or worm, e^4 , 85 which meshes with a worm-gear, e^5 , on the brush-shaft c' . If the conducting-rings be revolved at high speed, it is desirable that the brushes be revolved at a much slower speed, whether said brushes and rings be revolved 90 in the same or in opposite directions. It will be seen that if the several plates in each brush are lubricated their durability will be greatly enhanced, and also that if a lubricant be used which is a good electric 95 conductor greater efficiency will accrue, and hence I emp'oy mercury as a lubricant. Below each brush a trough, f , is so located that when supplied with mercury the brush will be partially bathed therein, and be enabled to 100 take up between its plates more or less of said lubricant, and also to carry more or less thereof upon its outer surfaces or periphery, and thus not only to obviate undue wear at the 105 contact-points, but also to maintain perfect electrical contacts not only as between the brush and the conducting-ring, but also as between the several plates of the brush.

As hereinbefore stated, I am aware of the extensive and varied use of mercury in electrical apparatus, and have myself employed it heretofore in connection with rolling or moving contacts in machines devised by me; but I know of no prior instance in which mercury has been employed as a lubricant for a 110 revolving brush composed of laminations or plates, nor any prior instance wherein a mercury-bath has been employed with a revolving brush or revolving conductor of any kind 115 positively driven, and thereby so controlled 120 as to prevent the mercury from being unduly displaced, as is the case with a brush revolving at a high speed in contact with mercury.

I will next refer to Figs. 8 to 11, inclusive, wherein I also illustrate means for positively 125 driving said brushes. In said Figs. 8 and 9 I have illustrated another form of dynamo, but for the purposes of this specification I need only refer to the revolving armature A as one having a series of conducting-bars, a , each having conducting-rings b , as before described; but said rings have flat flanges b' , instead of

the sharp edged flanges before described. The conductors or brushes B' here shown are like those last described, but in this case each brush is flatly pressed, near its periphery, 5 against the flat face of a conducting-ring flange, b'. The several brushes are here mounted upon hubs or sleeves g, composed of insulating material, (or said brushes are otherwise insulated from each other,) and said hubs with- 10 in certain limits can slide longitudinally on the shaft e, but are revolved therewith. Two sets of brushes and two hubs are here shown, and between said hubs there is an expansive spiral spring, g', on said shaft e, which causes each of 15 the brushes on each hub to engage under a yielding contact with its respective conducting-ring, thus enabling disk-conductors to be used which have in themselves little or no resiliency, in which case the intervening rings 20 at the hub may be composed of elastic insulating material, and thus provide for a yielding contact of any one disk-conductor independently of others on the same sleeve or hub. In this machine each brush has its mercury- 25 trough f, and although in this case I also use said troughs as the terminals of certain outside stationary conductors, f'', required in a machine of this type, it is to be understood that the use of said troughs or the mercury 30 therein as such terminals in no manner relates to my present invention, the lubricating effect now sought by me being the same, regardless as to what additional use said troughs or their mercury may be applied. As shown in said 35 Figs. 8 and 9, the shaft e of the armature A is the source of power for revolving the brushes. At the outer end of the shaft e there is a screw-thread or worm, e', which meshes with a worm-gear, e², on a vertical shaft, e³, having near its 40 lower end a thread or worm, e⁴, which in turn meshes with a large worm-gear, e⁵, on the brush-shaft e, all substantially as before described.

For further illustrating the varied utility 45 of the main features of my invention, I will refer to Figs. 12 to 15, inclusive, wherein I show the hub of a revolving armature common to such machines as involve the use of a commutator—as, for instance, the Gramme or 50 the Siemens machines. As here shown, the several armature-conductors terminate at the hub A² in segmental contact-blocks h, and my novel brushes B are employed therewith. With machines of this class the available area 55 of contact with the brushes is of necessity much less than can be successfully employed in the unipolar machines before described, and hence instead of mounting my brushes B upon shafts which are parallel with the axis 60 of the armature, said shafts e² are at right angles thereto, and instead of requiring several series of brushes, but two of these are needed—one at each side of the hub. In this case each brush is positively driven by means of its own 65 worm-gear e⁶ and its worm and worm-shaft e⁷; but both of these latter are driven by means

of corded belts running in grooves on the armature-shaft and engaging with large grooved pulleys on said worm-shaft e⁷. Each of these brushes has its lubricating mercury 70 bath or trough f, and these latter also serve as the electric terminals of the machine. In machines of this type the advantages accruing from the use of a positively-driven brush, with or without its mercury-bath, are not dependent 75 upon a brush of any special form, it being obvious that if the conducting disk or brush be composed of practically non-resilient material—a disk of carbon, for instance—it could be made to engage with yielding contact by 80 the use of a spring at its hub, as already described.

While I prefer that my novel brushes be constructed as shown in Figs. 4 or 7, and make specific claim to such as are composed 85 of a series of plates or laminations so formed and arranged with relation to each other that each plate affords a side contact-surface, near its periphery, I do not limit myself thereto, it being, as I believe, broadly new to construct 90 an electric annular or disk-shaped brush composed of a series of plates or laminations, all of which can engage at or near their peripheries in electric contact with a moving surface in a plane at right angles to the axis 95 of said disk. This result is not dependent upon the peculiar cuts or forms illustrated in Figs. 4 and 7, but can be produced with a brush composed of a series of laminations or plates, each formed and the whole arranged 100 with relation to each other, as illustrated in Fig. 16, Sheet 1, of the drawings. In this form of brush, there is a series of laminations or plates, d, all having an axial opening, and each is concavo-convex adjacent to its periphery. 105 Commencing from an outer plate on one side of the brush, each succeeding plate is larger in diameter than the preceding plate, and the edges of all of said plates occupy substantially the same plane, so that when the brush is in service 110 each plate has its own specific point or points of contact. This form of brush is, like the others, well adapted to carry mercury as a lubricant, and possesses the desired resiliency and operates with a peculiar frictional contact 115 which renders it highly effective. When a brush is composed of a single series of the concavo-convex laminations or plates, as shown, it is well adapted for use in the manner illustrated in Figs. 8 and 12; but two of such series 120 of plates should be employed in a brush if it is to be employed with sharp edged flanges or double contact-surfaces, as shown in Figs. 1 and 6.

It will be readily seen that if the brush in 125 the form illustrated in Fig. 16 should have all of its plates radially slotted at frequent intervals its resiliency would be greatly increased and render it as sensitive in that respect as the other forms of brush previously described, 130 and that this construction would resemble and be in substance a mass of flat wires an-

nularly arranged in disk form, and, inasmuch as the end of each wire or arm in each plate would afford the contact-surface, said wires or arms could be composed of round wire 5 without materially affecting the results. So also will it be seen that the plates shown in Fig. 4 might also be radially slitted at frequent intervals without materially impairing their value, the main point to be observed being that the brush be in the form of a disk and adapted to afford lateral contact as distinguished from peripheral contact.

While my novel brushes are of special value for use in connection with revolving contact- 15 surfaces because of the low resistance secured by the extensive areas of contact and the considerable conductive capacity of each plate, as well as the massing of all the plates in close electric contact, it will be obvious that they 20 will be equally effective and useful if used in connection with contact-surfaces which reciprocate, and even with such as are stationary—as, for instance, either form of the novel brush shown will operate effectively in connection 25 with a flat-faced stationary conducting-bar.

The rotative capacity of a brush composed of laminations or plates according to my invention I deem of value, even if said brushes be not positively driven—as, for instance, if 30 in the machine shown in Fig. 8, the brush-shaft were uncoupled from the armature-shaft the several brushes could at proper intervals be partially rotated, and thus present fresh 35 surfaces for contact, and more or less of the lubricant would be carried by the brush.

Having thus described my invention, I claim as new and desire to secure by Letters Patent—

1. The combination, substantially as hereinbefore described, of one or more disk-shaped 40 electric conductors, a rotative shaft on which said conductors are mounted, and gearing by which said shaft and the brush-conductors are positively rotated.

2. The combination, substantially as hereinbefore described, of one or more disk-shaped 45

electric conductors, a rotative shaft on which said conductors are mounted, gearing by which said shaft is positively driven, and a mercury-bath for lubricating each conductor.

3. A disk-shaped electric-brush conductor 50 composed of a series of laminations or plates, each affording at or near its periphery a surface for electric contact in a plane substantially at right angles to the axis of said disk.

4. A disk-shaped electric-brush conductor 55 composed of two series of laminations or plates, each plate affording at or near its periphery a surface for electric contact in a plane substantially at right angles to the axis of said disk, and having the contact-surfaces of the two series of plates coincident with each other, substantially as described, whereby a conductor with which said brush is to operate can be embraced between said two series of plates at 60 or near their peripheries.

5. A disk-shaped electric-brush conductor 65 composed of laminations or plates having an axial opening, a radial slit, and a portion thereof cut away on eccentric lines, substantially as described.

6. The combination, with a disk-shaped brush-conductor composed of laminations or plates and axially mounted, of a mercury-bath 70 for lubricating said plates, substantially as described.

7. The combination, substantially as hereinbefore described, of a rotative shaft and one or more electric brushes mounted thereon, each composed of a series of laminations or plates massed together and affording a contact-surface in a plane substantially at right angles to the axis of the brush, whereby many or all of 80 said plates may be successively engaged in lateral contact with a co-operating electric conductor.

RUDOLF EICKEMEYER.
